WILLIAM N. BARTHOLOMEW, OF NEWTON CENTRE, MASSACHUSETTS.

Design No. 4,676, dated February 28, 1871.

DESIGN FOR A DRAWING-CHART.

The Schedule referred to in these Letters Patent and making part of the same.

To whom it may concern:

Be it known that I, WILLIAM N. BARTHOLOMEW, of Newton Centre, in the county of Middlesex and State of Massachusetts, have invented a new and original Design for Charts, which I term BARTHOLOMEW's Primary School Drawing-Charts, and of which the following is a specification.

The design consists of a chart composed of linen, paper, or other pliable material, having printed, or otherwise formed upon its surface, the figure of a slate, as shown in the drawing, a representing the chart and b b' the slate.

Within the slate-frame b' are printed, drawn, or otherwise formed, the marks or figures which it is intended the scholar shall copy.

A number of these charts, each having the figure to be drawn located within the slate-frame design, may be attached to a stick or supporting-piece, c, which is hung up on the wall of the school or other place where the charts are to be used.

The teacher can turn or fold back the charts like the leaves of a book, until he comes to the chart containing the figure which he desires the scholars to copy.

The object of the chart is to facilitate the instruction of children in drawing.

It enables them to judge accurately of distance, direction, and position, by putting before their eyes an example or figure placed within a slate-frame, which example they can, on that account, the more easily reproduce, the position of the printed example enabling them to determine more accurately what they must do in order to copy the design or example correctly upon their own slates.

What I claim, and desire to secure by Letters Patent, is—

The design for drawing-charts, as herein shown and described.

In testimony whereof I have hereunto set my hand in the presence of two subscribing witnesses.

WM. N. BARTHOLOMEW.
